UNITED STATES PATENT OFFICE.

HOSEA M. KRAUSER, OF NORRISTOWN, PENNSYLVANIA.

CLOTHES-PROP LINE-FASTENER.

1,149,923.

Specification of Letters Patent. Patented Aug. 10, 1915.

Application filed August 21, 1914. Serial No. 857,867.

To all whom it may concern:

Be it known that I, HOSEA M. KRAUSER, a citizen of the United States, and a resident of Norristown, in the county of Montgomery and State of Pennsylvania, have invented a new and Improved Clothes-Prop Line-Fastener, of which the following is a full, clear, and exact description.

This invention relates to improvements in clothes line props and more particularly to an improved fastener for securing the upper end of the prop to the clothes line, whereby disengagement of the prop from the line or vice versa with consequent releasing of the line from the notch of the prop and resultant falling of the clothes to come in contact with the ground, will be obviated.

Another object of the invention is to provide an improved clothes line prop fastener which may be applied to props of ordinary construction having the usual V-shaped notch in their upper ends and in which said fasteners are so constructed that the line may readily enter the narrow portion or crotch of the notch but will be prevented from disengaging therefrom under the influence of high winds or swaying of the line with the clothes but which will necessitate the manual releasing of the line.

With the above and other objects in view, the invention resides in the peculiar combination and arrangement of parts to be hereinafter more fully described, illustrated and claimed, it being also an object to provide a device which is simple in construction, durable and efficient.

Reference is to be had to the accompanying drawings forming a part of this specification, in which similar characters of reference indicate corresponding parts in all the views, and in which—

Figure 1 is a side elevation illustrating a fragmentary portion of a clothes prop having its upper end provided with one form of the improved fastener; Fig. 2 is a view taken at right angles to Fig. 1 looking toward the left; Fig. 3 is a view similar to Fig. 1 but showing another form of fastener; Fig. 4 is a view taken at right angles to Fig. 3 with the upper portion of the prop broken away and shown in section; Fig. 5 is a perspective view of a still further modified form of fastener.

Many fasteners provided to prevent dis-

placement of a clothes line from a prop, or vice versa, have been provided and some of these devices possessed the disadvantages of requiring sliding mechanism associated with the prop which might be very readily accidentally released or in which the line, whether it be of fabric or wire, would be likely to disengage itself from the fastener due to the instability of the latter and therefore its likelihood of breaking or getting out of order.

The present invention is devised to overcome these objections, and in illustrating the application thereof the upper portion 10 of an ordinary clothes prop is shown having a notch 11 in its upper end. This notch is usually of V-shape, as shown, and the line is adapted to enter into the crotch portion 12 thereof from which it is designed to be held from displacement. The improved fastener provided for this purpose comprises a single section of wire or resilient metal bent intermediate its ends to provide an upper connecting bight portion 13 of a slightly greater length than the width of the prop so as to straddle the latter and dispose the side portions 14 at right angles to the bight portion 13. The side portions adjacent to the bight are curved to extend at an angle across the notch and are then rebent, as shown at 15, to provide depending projections to prevent displacement of the line therefrom and beneath oppositely curved bottom retaining concavities produced by portions 16 extending at spaced distances from the curved sides near the bight or connecting portion which co-operates with the wall 17 to provide a flaring entrance to permit positive and convenient engagement with the line.

The sides depend from the curved portions 16 and are provided with spring coils or the like 18, preferably so wound as to dispose the side portions thereabove at a spaced distance from the side faces 19 of the prop, as shown at 20, whereby the upper portion of the fastener will have free movement. Suitable fastening devices are loosely engaged through the coils and secured to the prop to permit said spring coils to resiliently act there-around and said fastening devices are indicated as screws 21 for purposes of illustration. From these screws the free ends or extremities 22 of the strand

or side portions of the fastener depend and these extremities are anchored to the sides of the prop to have slight relative movement, as by means of the engagement of 5 staples 23 therewith. In this manner when the line 24 is engaged between the upper portion of the fastener and the wall 17, the fastener may be forced to the left to the dotted line position shown in Fig. 1 due to 10 the resiliency of the fastener and thereby permit the line to pass into the crotch of the notch under the portion 15 and beneath the curved portions 16 and thereby held from displacement. This is due to the fact that 15 the portions are slightly off center and therefore any tendency to displace the line upwardly would exert pressure against the curved portions or bottom notches 16 adjacent to the curved portions 15 and in an 20 attempt to displace the line the fastener will be moved to the dotted line position to the right in Fig. 1 to more positively hold the line in position and thus prevent displacement of the prop relative thereto.

25 In Figs. 3 and 4 of the drawings the structure of the fastener is the same with the exception that the bight portion instead of being disposed at right angles to the side portions, is provided with curved sides 25 gradually narrowing toward the bight portion so as to contact with the edges of the adjacent wall of the notch of the prop, while the upper portion of the fastener, as shown in Figs. 1 and 2, is adapted to clear said side 30 portions. In both instances, however, the upper portions are located substantially wholly within the notch and are thereby protected from injury should the prop fall to the ground, as distinguished from other 35 devices employing fasteners which project from the upper ends of the props or are located at one side only. In this form of the invention the extremities of the fastener are also anchored by means of suitable fastening 40 devices in the form of screws 26 in lieu of being straddled by staples as shown in Figs. 1 and 2, but these screws are loosely engaged 45 through coils 27 at said extremities so that they are not absolutely rigid and thus added 50 resiliency is given to the upper portion of the fastener.

55 In Fig. 5 of the drawings the fastener is the same as that described in connection with Figs. 1 and 2 except that instead of anchoring the lower ends by means of a staple or similar fastener, said extremities are provided with inwardly directed points or prongs 28 adapted to be lightly driven into the wood so as to allow the necessary resiliency to attain the objects heretofore referred to, due to the points or prongs working loose 60 while still held from outward displacement by the screws or fasteners 21. This form of fastener will actuate the same as that described in connection with Figs. 1 and 2 but

in the structure shown in Figs. 3 and 4 the curved portions 25 will contact with the edges of one wall of the crotch when an attempt is made to displace the line, as indicated in dotted lines in Fig. 3.

70 Advantage is claimed for a fastener which engages on both sides of the prop exteriorly of the notch therein as the line is caused to bind against the edges of the opposed walls of the notch at the crotch thereof to be more 75 securely held from displacement, and it is also stated that the size of the line is immaterial as to the operation described, so that any size line, whether wire or rope, will be 80 positively held from displacement without requiring any special construction of prop.

Having thus described my invention, what I claim as new and desire to secure by Letters Patent is:—

85 1. A clothes prop fastener adapted for use with a prop having a notch in its upper end, comprising a single section of resilient metal bent intermediate its ends to provide a bight portion and sides extending therefrom, said sides coöperating with one wall of the notch 90 to provide an entrance portion and being rebent upwardly and downwardly to provide retaining portions, the upper portions of said sides being curved away from said wall of the notch and over said retaining portions, said sides being bent to form coils 95 whereby the upper portion of the fastener is rendered resilient with the sides spaced from the sides of the prop, means engaged through the coils for anchoring the fastener to the prop and means at the lower ends of the side portions of the fastener to additionally anchor the same to the prop and permit 100 resilient movement of the upper portion from the coils upward.

105 2. A fastener for clothes props having a V-notch, comprising a resilient member straddling the prop and notch thereof spaced between the walls of the latter and having an upper portion coöperating with one wall of the notch to provide a flaring entrance opening, a curved portion providing a downwardly opening notch partially off center with respect to the crotch of the notch in the prop and a portion depending 110 therefrom to be resiliently anchored to the prop to dispose the upper portion adjacent to the notch therein.

115 3. A clothes line fastener adapted for use with a prop having a notch in its upper end, comprising a section of resilient metal bent intermediate its ends to provide a bight portion and sides extending therefrom at the sides of the prop with which the ends of the notch communicate, said sides coöperating 120 with one wall of the notch to provide an entrance portion and being rebent upwardly and downwardly to provide retaining portions with projections overlying the sides of the prop, and means to anchor the extremi- 125 130

ties of the sides of the fastener to the opposed faces of the prop about midway of the width thereof.

4. A fastener for clothes props having a V-notch, comprising a resilient member straddling the prop and notch thereof at spaced points between the walls of the latter, said resilient member having a curved upper portion coöperating with one wall of the notch to provide a flaring entrance opening, curved portions providing downwardly opening notches and prongs depending therefrom to be resiliently anchored to the prop to dispose the upper portion adjacent to the notch therein.
5. A clothes prop line fastener having a clothes line receiving notch comprising a

section of resilient material having a curved upper bight portion with sides located in proximity to and equidistantly from one side of the notch, said studs projecting downwardly over the opposite faces of the prop, said section having a bottom concavity and means to anchor the lower portion of the fastener of the prop to the sides thereof with which the ends of the notch communicate.

In testimony whereof I have signed my name to this specification in the presence of two subscribing witnesses.

HOSEA M. KRAUSER.
